UNITED STATES PATENT OFFICE.

MONROE DAVIS, OF ENID, OKLAHOMA.

THRESHING-MACHINE.

1,251,187.

Specification of Letters Patent. Patented Dec. 25, 1917.

Application filed July 19, 1917. Serial No. 181,607.

To all whom it may concern:

Be it known that I, MONROE DAVIS, a citizen of the United States, residing at Enid, in the county of Garfield and State of Oklahoma, have invented certain new and useful Improvements in Threshing-Machines; and I do declare the following to be a full, clear, and exact description of the invention, such as will enable others skilled in the art to 10 which it appertains to make and use the same.

My invention relates to improvements in threshing machines, and more particularly to means for effectively separating the grain 15 from the chaff, the present invention being similar in a number of respects to my U. S. Patent 1174398 of March 7, 1916, but possessing a number of improved features of construction.

20 As will be evident from the foregoing, the principal object of the invention is to provide means for effectively separating the grain from all chaff and dust whereby it may be sacked as discharged from the machine, without the necessity of any other cleaning.

25 A further object is to provide a novel type of sacking device so constructed as to cause the travel of a current of air therethrough in the reverse direction from that in which the material being sacked is traveling, thus insuring that all dust and the like shall be removed from the grain before it is discharged.

30 With the foregoing general objects in view, the invention resides in the novel features of construction and unique combination of parts to be hereinafter fully described and claimed, the descriptive matter being 40 supplemented by the accompanying drawings which form a part of this specification and in which:

Figure 1 is a side elevation of the improved machine;

45 Fig. 2 is substantially a central vertically longitudinal section;

Figs. 3, 4 and 5 are vertical transverse sections on the planes of the lines 3—3, 4—4 and 5—5 of Fig. 2 respectively;

50 Fig. 6 is an enlarged vertical section of the discharge end of the sacking device;

Fig. 7 is a horizontal section on the plane of the line 7—7 of Fig. 6;

Fig. 8 is a detail side elevation of the parts shown in Fig. 7; and

Fig. 9 is a detail horizontal section on the plane of the line 9—9 of Fig. 8.

In the drawings above briefly described, the numeral 1 designates a horizontally disposed threshing cylinder suitably mounted upon a frame 2 having front and rear earth engaging wheels 3 and 4 respectively, the front wheels being provided with the usual or any preferred type of tongue 5, or any other suitable means by which the machine 55 may be drawn from place to place. A line shaft 6 extends coaxially through the threshing cylinder 1 and projects beyond the rear end thereof through a straw discharge housing 7 and a chaff discharge housing 8 both 60 of which will be hereinafter described, it being upon the shaft 6 that a plurality of suitably constructed and arranged beaters 65 9 are disposed for whirling the incoming grain around and separating the straw from 70 the grain proper by centrifugal force. 75

The inlet for the unthreshed grain is in the form of a pair of pipes 10 and 11 respectively, the pipe 10 being carried by the inlet end of the threshing chamber 1, whereas the pipe 11 extends into the outer end of said pipe 10 and at its upper side is hinged thereto at 12. It will be observed that the lower side of the pipe 10 extends beyond the hinge line and that although a snug engagement will exist between the two pipes 10 and 11 when they are in alignment, a gap 13 will 80 exist when the pipe 11 is swung upwardly as shown in full lines in Fig. 2. This gap is highly essential, since when the grain is being drawn into the threshing chamber 1 by the action of the fan 15 in the fan housing 7, the air currents have a tendency to short circuit and thus to create a greater amount of suction through the upper portions of the pipes. 85 On account of the gap 14, however, an air blast will be directed across the lower sides of the bundles of grain as they enter the pipe 10 from the pipe 11, this blast serving to direct the bundles upwardly into the 90 threshing chamber 1, without permitting them in any manner to lodge in the inlet pipes. 95

The grain, upon entering the chamber 1, is so acted upon by the feeder arms 9 that the grain is separated from the straw, the latter being discharged into the fan housing 100 105

7, whereas the threshed grain will fall from the chamber 1 through a longitudinal grain outlet 16 in the lower side thereof. The housing 19 is provided with an outlet spout 17 and in order that this spout may be raised and lowered for stacking the straw at different elevations, the entire housing is preferably mounted so that it may rotate. This may be accomplished in numerous ways, but 10 I prefer to provide one end of the housing 7 with an outstanding annular flange or collar 18 which surrounds a similar outstanding collar 19 on the delivery end of the threshing chamber 1, the other end of the housing 15 7 being suitably supported upon a bearing such as that indicated at 20, this bearing being carried by a transverse bar 21 of the frame 2. For raising and lowering the spout or pipe 17, a cable 22 is preferably 20 provided, said cable passing over a pulley 23 on the upper end of a post or the like 24 which rises from the machine, the free end of the cable being wound upon a suitable windlass 25 which is equipped with a dog 26 25 for holding it against retrograde rotation until required.

After leaving the threshed grain outlet 16, the grain is received in a horizontally elongated casing 27 which extends beneath the 30 greater part of the threshing chamber 1, said casing being provided with a trough-like screen 28 for catching any chaff which may be discharged with the threshed grain. The grain, however, will drop to the bottom of 35 the casing 27 and is adapted to be carried from this casing into a threshed grain discharge housing 29, by means of a screw conveyer or the like 30 which is positioned adjacent the bottom of the casing in question. 40 From the housing 29, the grain is carried upwardly within a grain discharge passage 31, by an endless belt conveyer 32 and is discharged into an inclined portion 33 of said passage, said portion delivering into a 45 sacking pipe 34 which possesses novel features of construction yet to be described.

It is to be understood that any preferred means could be employed for driving the conveyers 30 and 32, belts 35 and 36 being preferably employed, however, for driving said conveyers from the line shaft 6.

Another screw conveyer 37 is driven by a belt or the like 38 from the shaft 6 and is positioned above the screen 28 for the purpose of feeding the chaff from the latter into the housing 29. This chaff is prevented from settling in the housing 29, however, by the pneumatic means now to be described.

A chaff discharge easing 39 communicates 60 with the housing 29 at one end and at its other end discharges at 40 into the eye of the fan housing 8, a suitable fan 41 being located in said housing and mounted on the shaft 6, so that when the shaft is rotated, 65 the fan 41 will create suction in the casing

39 to draw the chaff therefrom and discharge it into the housing 8, from which it is delivered through a suitable outlet 42. It is highly possible that some of the threshed grain may be carried from the housing 29 70 with the current of air flowing into the fan housing 8, and in order to check this grain and prevent the discharge thereof through the outlet 42, a vertical baffle plate 43 is 75 preferably employed within the casing 39, said plate serving to check the outward movement of the grain and to return it to the bottom of said casing. This bottom is in the same plane as the bottom of the casing 27, and a screw conveyer 44, mounted on the 80 same shaft as the conveyer 30, is positioned adjacent said bottom to return any grain dropping thereon to the housing 29. By the provision of the casing 39, the fan housing 8, and the fan 41, it will be obvious that a 85 great amount of chaff which would otherwise be discharged with the threshed grain, will be blown out of the separate discharge 42 provided for that purpose. It is nevertheless necessary to provide an auxiliary means 90 for still further drawing small particles of chaff and dust from the threshed grain before it is finally discharged, this end being attained by the following construction.

A suction passage 45 leads from the upper 95 end of the sacking pipe 34 to the eye of the fan housing 8, so that the latter will create suction through said passage and through the pipe 34, thus removing any dust and fine particles of chaff and the like which may 100 still remain with the threshed grain as the latter is discharged into said pipe. During this separating action, some of the grain may possibly be carried from the pipe 34 through the passage 45, and in order that 105 this grain shall not be discharged into the housing 29 and thrown thereby from the fan 41, with the chaff, I provide a vertically disposed dead air chamber 46 which communicates at its upper end with the passage 110 45, whereas the lower end of said dead air chamber is provided with a door or the like 47 for placing it in communication with the housing 29, when a sufficient quantity of grain accumulates in said chamber to automatically open the door against the tension of the spring 48 which is provided for normally retaining it in closed position. Any preferred means could be employed for directing the grain from the passage 47 into 120 the dead air chamber 46, but I preferably employ a pair of pivoted valves 49 which are shown more particularly in Fig. 1, this arrangement being highly efficient and durable, yet simple and inexpensive.

By the construction just described, it will be obvious that no grain will be discharged from the machine with the chaff and that all of the grain which is collected in the dead air chamber 46 will be automatically 130

discharged at intervals into the housing 29 and will be carried from the latter to the sacking pipe 34 by the means provided.

At its outlet end, the sacking pipe 34 is 5 provided with a sleeve 50, the inner end of said sleeve being held in spaced relation with the end of the pipe 34, by suitable arms or the like 51. By this construction, an annular air inlet 52 is provided into which a 10 current of air will be drawn into the pipe 34 by the suction therein, said current being caused to travel reversely from the direction in which the cleaned grain is passing, whereby any dust and fine particles of 15 chaff will be removed therefrom. For controlling the strength of the current of air entering the inlet 52, a valve ring 53 is mounted slidably upon the pipe 34 and may be moved toward or away from said inlet and held in adjusted position by a set 20 screw or the like 54.

The outer end of the sleeve 50 is adapted to be received in the sack S, (Fig. 8) said end being provided with a channel 55 having outwardly projecting prongs 56 therein, upon which the sack is supported, a suitable sack tightener 57 being provided, said tightener having an operating handle 58 as shown most clearly in Figs. 7, 8 and 9. 30 Although this form of tightener is preferably employed, it will be obvious that other types could well be used, it being only necessary that the sack S be secured to the sleeve in such a manner as to prevent collapsing of the former.

In operation, the bundles of grain, or the loose grain, as the case may be, are fed into the outer end of the pipe 11 and by the suction within the threshing chamber 1, 40 this unthreshed grain is drawn into said chamber. In the chamber 1, the rapidly rotating arms 9 throw the grain outwardly by centrifugal force and rapidly whirl said grain so that all of the kernels are separated 45 from the straw, the latter being drawn from the threshing chamber into the fan box 7 and being discharged from the latter through its outlet pipe 17, whereas the threshed grain drops through the outlets 16 50 into the casing 27. The grain will fall through the screen 28, but the chaff and the like which may be discharged therewith, will be collected by said screen, the two conveyors 30 and 37 now serving to move the 55 grain and the chaff respectively into the housing 29. The grain falls to the bottom of this housing and is carried off by the conveyor 32 and discharged into the sacking pipe 34, whereas the chaff and dust are prevented from settling in the housing 29 by the 60 current of air drawn therethrough by the fan 41, this dust and chaff being discharged through the outlet spout 42. During this 65 operation, any grain which may possibly be drawn toward the outlet 40 with the chaff

and the like, will strike the baffle 43 and will thus be checked in its movement, so that it will drop by gravity onto the bottom of the casing 39, the conveyer 44 now serving to return this grain to the housing 29 so 70 that it may be discharged with the other.

The fan 41 serves not only to create suction through the casing 39, the housing 29, and the casing 37, but also creates such suction through the passage 45 so that a current 75 of air is drawn in the annular inlet 52 and moves through said passage in the reverse direction from that in which the threshed grain is traveling, thus finally cleaning the latter. All of the dust and chaff drawn through the passage 45, will be discharged into the fan box 8 and from the latter will be forced through the outlet 42. Any grain, however, which may possibly be drawn from the sacking tube 34, through 80 the passage 45, will be directed into the dead air chamber 46, by the valves 49 and will collect in the bottom of said chamber until the door 47 automatically opens to discharge this grain into the housing 29. 85

In some instances, it may be necessary to provide one or more auxiliary air inlets such as sliding doors 59, for the purpose of varying the strength of the draft of air drawn through the casing 39, but in other 90 cases it may not be necessary to employ such inlets, according to the use to which the machine is to be put. For instance if rice is to be threshed, after soaking thereof, it will be necessary to provide air currents of 95 100 extreme strength, in order that the damp chaff and the like may be carried off. On the other hand, when wheat, oats or other grain is to be threshed which is not soaked before the threshing operation, the currents 105 of air need not be of such strength.

From the foregoing, taken in connection with the accompanying drawings, it will be obvious that although the improved machine is of comparatively simple and inexpensive 110 construction, it will be highly efficient and durable. Particular emphasis is laid upon the improved separating means including the casing 27, the housing 29, casing 39, the fan 41, the suction passage 45, and the sacking pipe 34 with its adjustable air inlet 42. I also attach great importance to the inlet pipes 10 and 11 which are so connected as to form a crescent shaped air inlet 14 when 115 said pipes are moved into angular relation, and upon the casing 7 which is so mounted as to permit its discharge 17 to move vertically for stacking at different elevations. In addition to these several features, however, the general arrangement of parts 120 125 shown and described is considered highly important.

On account of the several advantages flowing from the specific details of construction shown and described, such details 130

constitute the preferred form of the improved threshing machine. I wish it understood, however, that within the scope of the invention as claimed, numerous minor changes may well be made.

I claim:

1. In a grain separator, the combination of a casing having a grain inlet, a screen across said casing to separate any chaff from the grain which may enter therewith, a housing having a cleaned grain outlet, means for moving the separated chaff and the grain from said screen and casing respectively into said housing, pneumatic means for removing the chaff from said housing before it settles therein, and means for returning any grain to said housing which may be carried therefrom with the chaff.
2. In a grain separator, the combination of a casing having a grain inlet, a screen across said casing to separate any chaff from the grain which may enter therewith, a housing having a cleaned grain outlet, means for moving the separated chaff and the grain from said screen and casing respectively into said housing, a chaff discharge casing communicating with said housing, and means for creating a draft of air through said chaff discharge casing to remove the chaff from the housing before it settles therein, said chaff discharge casing having means for returning any grain to said housing which may be carried therefrom with the chaff.
3. In a grain separator, the combination of a casing having an inlet, a screen extending across said casing to collect any chaff which may enter with the grain, a housing with which one end of said casing communicates, said housing having a cleaned grain outlet, a chaff discharge casing communicat-

ing with said housing and having pneumatic means for preventing settling of chaff therein, the bottom of said chaff discharge casing being in the plane with the bottom of the first named casing, said chaff discharge casing having means for depositing any grain on its bottom which may be carried from said housing with the chaff, a conveyer for moving the chaff from said screen into said housing, a second conveyer for moving the grain from the bottom of the first named casing into said housing, and a third conveyer on the same shaft with said second conveyer for returning the collected grain from the bottom of said chaff discharge casing to said housing.

4. In a grain separator, the combination of a housing into which the grain is deposited, said housing having a discharge passage for the grain, means for creating suction in said housing to draw off all chaff which may enter with the grain, and a suction passage leading from said grain discharge passage to said suction creating means.

5. In a grain separator, the combination of a housing into which the grain is deposited, said housing having a discharge passage for the grain, means for creating suction in said housing to draw off chaff which may enter with the grain, and a suction passage leading from said grain discharge passage to said suction creating means, a dead air chamber communicating at its upper end with said suction passage, means for directing any grain in this passage into said chamber, and means for discharging the collected grain from said chamber into said housing.

In testimony whereof I have hereunto set my hand.

MONROE DAVIS.
